DESIGN FOR A SIGN

Ramsay G. Regester, Philadelphia, Pa., assignor
to Gill Glass & Fixture Company, a corporation
of Delaware

Application August 21, 1935, Serial No. 58,219

Term of patent 7 years

To all whom it may concern:

Be it known that I, Ramsay G. Regester, a citizen of the United States of America and a resident of Philadelphia, in the county of Philadelphia and State of Pennsylvania, have invented a new, original, and ornamental Design for Signs, of which the following is a specification, reference being had to the accompanying drawing, forming a part thereof.

In the drawing:

Fig. 1 is a front elevational view of the sign, showing my new design;

Fig. 2 is an end elevational view; and
Fig. 3 is a top plan view of the same, the illustration of the panel being omitted.

The dominant features of the design are shown in solid lines and the immaterial portions are illustrated in dotted lines.

I claim:

The ornamental design for a sign, substantially as shown and described.

RAMSAY G. REGESTER.
